UNITED STATES PATENT OFFICE

2,466,193

COMPRESSOR FOR REFRIGERATING SYSTEMS

August P. Anderson, Goshen, Ind.

Application September 17, 1945, Serial No. 616,882

5 Claims. (Cl. 230—175)

1

The invention relates to compressors for refrigerating systems.

One object of the invention is to provide a compressor of the radial piston-type in which swinging movement is imparted to cylinders so they automatically function to control the intake to, and exhaust of fluid from the cylinders, for the compression of fluid by the piston.

Another object of the invention is to eliminate, from compressors of the radial piston type, the conventional intake and discharge valves for the cylinders which, in use, are subject to wear and leakage, become noisy, are sometimes rendered leaky by scale, metal cuttings, carbon, grit and the like in the fluid being compressed.

Another object of the invention is to provide a compressor of the radial piston type for refrigerating systems which comprises three or more radially movable pistons, which is simple in construction, light in weight, includes interchangeable parts, is balanced, and free from vibration.

Another object of the invention is to provide a compressor of this type which is simple and compact in construction and efficient in operation.

Another object of the invention is to provide a compressor of this type which can be produced and operated at low cost.

Other objects of the invention will appear from the detailed description.

The invention consists in the several features hereinafter set forth and more particularly defined by claims at the conclusion hereof.

In the drawings:

Fig. 1 is a central longitudinal section of a compressor embodying the invention taken on line 1—1 of Fig. 2.

Fig. 2 is a perspective of one of the compressor-cylinders.

Fig. 3 is a view of a portion of the face of the stationary head engaged by the cylinders.

Fig. 4 is a section illustrating one of the exhaust ports in the casing.

Fig. 5 is a section illustrating one of the intake ports in the casing.

Fig. 6 is a section taken on line 6—6 of Fig. 1.

Fig. 7 is a diagrammatic view of one of the compressor pistons and cylinders and the circular path of the axis of the pivot between the piston and the eccentric ring, illustrating the angle of a cylinder and its piston at the end of a compression stroke of the piston, and relative positions of the cylinder-port and the inlet and exhaust ducts in the crank-case at the end of the compression stroke.

Fig. 8 is a similar view illustrating the angular

5 10 15

2

position of a compressor-cylinder and its piston at the middle of a suction stroke of the piston and the relative positions of the cylinder-port and the inlet and exhaust ducts in the crank-case when the piston is at the middle of its exhaust stroke.

Fig. 9 is a similar view illustrating the angular position of a compressor-cylinder and its piston at the end of the suction stroke of the piston and the relative positions of the cylinder-port and the inlet and exhaust ducts in the crank-case, at the end of said suction stroke.

Fig. 10 is a similar view illustrating the angular position of the cylinder and its piston in the middle of a compression stroke and the relative positions of the cylinder-port and exhaust and inlet ducts in the crank-case when the piston is in the middle of said compression stroke.

The compressor comprises a stationary casing which may be supported in any suitable manner for housing the electric motor 16 for driving the compressor. This casing includes a cylindrical section 10 having an integral cross-wall or head 11 and a removable upper head 12, which provide a sealed enclosure for the electric motor 16. The casing also comprises a crank-case section which includes a cylindrical wall or crank-case 17 with an integral lower-end wall which, with the head 11, form a housing for the operating elements of the compressor, and is adapted to retain a column 30 of lubricating oil. The upper-end of the crank-case is provided with a flange 19 which is removably secured by bolts 20 to a flange 21 around the head 11 for access to the compressor. A head or frame 28 is stationarily supported in the crank-case in longitudinally spaced relation from head 11, by a series of spacer bolts 30, the upper ends of which are screw-threaded into head 11. A shaft 23 of the rotor of electric motor 16 is journaled in a bushing 24 in a hub 25 on head 11 and a bushing 26 which extends through and is fixed in the hub of head 28. A thrust-bearing 29 is provided for shaft 23.

Shaft 23 extends through the head 11 and into the head 28 and has keyed thereto, between said heads, an eccentric 44 for operating a series of radial pistons. Eccentric 44 is provided with a hub 45 which is secured on shaft 23 by a nut 46 which clamps said hub between a collar 47 engaged by said nut and a collar 48 which engages 50 a shoulder on said shaft. A weight 44a is integrally formed with eccentric 44 and functions as a counter-balance. The eccentric 44 fits in a ring 41 for operating the compressor pistons by power from the motor 16.

The compressor is exemplified with a series of

55

three radial cylinders 32 which are symmetrically disposed around the axis of shaft 23 and are confined for pivotal movement between the confronting faces of heads 28 and 11. Pistons 39 are axially slidable in said cylinders 32, respectively. Each cylinder 32 is provided on its opposite sides with co-axial trunnions 33 which are journalled in sockets 34 in heads 11 and 28, for pivotally supporting the cylinder to swing in a plane parallel with the plane of rotation of eccentric 44 or transversely to the axis of shaft 23. Each piston has a rigid or integral stem which is pivotally connected to ring 41 which fits around and is operated by eccentric 44. Pins 42, which pivotally connect ring 41 and pistons 39, are operated by the eccentric 44 to impart movement to the pistons 39 for moving them axially in cylinders 32 for suction and compression strokes and to operate the pistons angularly for swinging the cylinders imparting compound angular and axial movement to the pistons which imparts pivotal movement to the cylinders.

A plunger 39^a is slidably fitted in a pivoted cylindrical guide 39^b which is provided with trunnions 39^c which are journalled in co-axial sockets in heads 11 and 28. Plunger 39^a is provided with a rigid or integral stem 40 which is secured to ring 41 by rivets 40¹. Plunger 39^a and the pivoted cylinder 39^b constitute means for controlling the angular movement of ring 41 relatively to the axis of shaft 23 to cause the pistons 39 of the compressor and cylinders 32 to swing on the axes of trunnions 33 and control the pivotal movement of the cylinders in the crank-case, to impart predetermined compounded sliding and pivotal strokes to pistons 39, and pivotal strokes to cylinders 32.

Each compressor cylinder 32 is provided with a port 50 in its side which faces the head 11, through which fluid alternately passes into and is discharged from the cylinder from intake and exhaust ducts formed in the contiguous face of head 11. Each cylinder 32 is provided with an integral pad 32^a having a face which slidably fits against the face of a pad 35 formed on the contiguous face of head 11. The faces of pads 34 on cylinders 32 are pressed into wiping contact with the contiguous faces of pads 35 by springs 36 to maintain a fluid-tight fit between said faces. Springs 36 are confined in the trunnion-sockets 34 in head 28 and engage the trunnions 33 in said head to urge the cylinders 32 into contact with the pads 35 on head 11. A similar spring may be provided for cylindrical guide 39^b.

The low pressure fluid or gas from the suction line of a refrigerating system is delivered into the crank-case by a pipe 52 which is connected to head 11 and communicates with the chamber in crank-case 17. Head 11 is provided with an angular intake duct 51 for each cylinder 32 which communicates with the chamber in the crank-case and terminates in the face of a pad 35 on said head, for communicatively connecting cylinder-port 50 to receive fluid during the suction stroke of the piston 39. A discharge or high pressure duct 54 is formed in head 11 for each cylinder 32 and is communicatively connected with one of the cylinder-ports 50 during the out pressure stroke of a piston 39. Discharge ducts 54 for all of the cylinders 32 are communicatively connected to branches of a header 55 which is connected to deliver compressed gas to the condenser of the refrigerating system. Each branch of header 55 includes a check-valve 56. The swinging movement of cylinders 32 are utilized to produce a

valve action between the cylinders 32 and head 11 for alternately controlling, through ports 50, the intake of gas from a duct 51 and the discharge of compressed gas to a duct 54. The swinging movements of cylinders 32 also produce a wiping action between the faces of pads 34 and 35 which tends to keep the contiguous faces free from grit or dirt.

The lower portion of the crank-case 17 is adapted to retain, or serve as a sump for, a supply of oil for lubricating the bearings of the compressor. A vane type pump 60 includes an impeller 61 which is secured to and driven by the lower end of shaft 23 and a casing 62 for the impeller which is secured by screws 63 to the lower end of head 28. The intake 64 for the oil extends below the level of the column of oil maintained in the crank-case 17. An outlet pipe 65 for oil from casing 62 is connected to a duct 67 in head 11 for lubricating the bearing in bushing 24 for shaft 23 and to a duct 66 in head 28 for lubricating the bearing in bushing 26 for said shaft. Oil which is carried upwardly through bushing 24 passes to ducts 69 in head 11 for lubricating the bearings for the upper trunnions 33, and leaks back into the crank-case. Ducts 68 in head 28 conduct oil from the column in the crank-case to the bearings for the lower trunnions 33.

The operation of the compressor will be as follows: eccentric 44 is rotated continuously in one direction by shaft 23 which is driven by the electric motor 16 and will operate ring 41 to impart axial sliding and oscillatory movement to the pistons 39 which will impart oscillating movement to cylinders 32. During each rotation of eccentric 44, plunger 39^a, operating in the pivoted guide 39^b, will control the angular movement of ring 41 around said eccentric and the movement of pins 42. The oscillatory movement of the cylinders 32 will move alternately their ports 50 for intake of gas from ducts 51 and for the discharge of compressed gas through ports 50 and ducts 54. The angular movement of ring 41 on eccentric 44 is controlled by the fixed connection between said ring and plunger 39^a which is slidable in cylindrical guide 39^b which is pivotally movable in the sockets for trunnions 39^c. These elements cause each of the axes of pins 42 between ring 41 and pistons 39 to travel in circles indicated by the dotted circle marked "X" in Figs. 7 to 10. During each revolution of eccentric 44, the ring 41 will be operated to impart compound reciprocating and angular intake and compression strokes to the pistons 39 in rotative succession. The angular movement of the cylinders 32 produced by pistons 39 from ring 41 will, during each rotation of eccentric 44, control communication through each cylinder-port 50 with its intake duct 51 and its discharge duct 54. Assuming the pistons 39 to be at the end of its outstroke, as illustrated in Fig. 7, the port 50 will be disposed between its associated ducts 51 and 54 and closed. Ring 41, during the inward movement or suction stroke of piston 39, will swing each cylinder 32 to register its port 50 with the intake duct 51 to admit fluid into the cylinder 32, as illustrated in Fig. 8. When the piston 39 reaches the end of its suction stroke, as illustrated in Fig. 9, cylinder-port 50 will again be closed. During the succeeding outstroke of pistons 39, each cylinder 32 will be shifted angularly, as illustrated in Fig. 10, and its cylinder-port 50 will be in communication with its associated discharge duct 54 and discharge the fluid under compression to the header 55. Each piston 39 will be operated in ro-

tative succession to produce a substantially constant outflow of compressed fluid.

In this operation, this piston 39 which is connected to ring 41 diametrically opposite the guide plunger 38^a and the cylinder 32 for said piston, if the pin 42 connecting said piston and ring is spaced the same radial distance from the axis of shaft 23 as the other pins 42, would be shifted a greater angular extent than the pins 42 for the other pistons 39. To compensate for this variation, the axis of the trunnions 39^c for the cylindrical guide 38^a and the axis of the diametrically opposite cylinder 32 are spaced a somewhat greater distance from the axis of shaft 23 than the trunnions for the other cylinders. This results in imparting angular movement of the same degree to the outer ends of all the cylinders 32 and makes it possible to provide intake ducts and exhaust ducts equi-distantly spaced apart, for producing the same relative movement between the cylinder-ports 50 and the intake ducts 51 and exhaust ducts 54 for all of the cylinders 32. In this manner, the pivotal or angular movements of the cylinders 32 imparted thereto by the pistons 39 and eccentric 44, the ring 41 and pistons 39 will automatically control the intake of the fluid into the cylinders and the discharge of the compressed fluid from the cylinders in rotative succession.

The invention exemplifies a compressor of the radial piston and cylinder type in which the flow of gas to and from the cylinders is automatically controlled without conventional poppet, or slide valves. The compressor is simple and compact in construction and the operating parts are automatically lubricated. Upon removal of the crank-case 17 from the casing section which houses the electric motor, the compressor parts become readily accessible for repair or replacement.

While the invention has been described and is particularly advantageous for use with refrigerating gases, it is obvious that it may be used for other purposes. The invention is also applicable to compressors with any suitable number of cylinders and pistons.

The invention is not to be understood as limited to the details described, since these may be modified within the scope of the appended claims without departing from the spirit and scope of the invention.

Having thus described the invention, what I claim as new and desire to secure by Letters Patent is:

1. A compressor comprising a series of pivotally mounted cylinders, pistons axially slidable in and pivotally movable for pivotally shifting the cylinders, a driven eccentric, a ring on the eccentric, means including an element rigid with and for controlling the angular movement of the ring for imparting sliding and pivotal strokes to the pistons for pivotally shifting the cylinders, and means controlled by the pivotal movement of the cylinders for controlling the intake and exhaust of fluid for compression in the cylinders by the pistons.

2. A compressor comprising a casing adapted to retain oil and a head, a driven shaft extending through the head, an eccentric on said shaft, and in the casing, a ring on eccentric, a second head mounted in the casing in spaced relation to the first head, cylinders disposed between the

heads and provided with trunnions for supporting the cylinders for pivotal movement and with faces fitting against the first head, springs mounted in the second head for pressing the cylinders against the first head, pistons axially slid-
5 able in the cylinders and provided with fixed stems pivotally connected to the ring, means for controlling the angular movement of the ring to impart axial movement of the pistons in the cylinders and their pivotal movement for swinging the cylinders between said heads, and intake and exhaust ducts in said first head, the cylinders being provided with ports movable between said ducts for controlling the flow of fluid be-
10 tween said ducts and the cylinders.

3. A compressor comprising: a casing, a series of cylinders pivotally mounted in the casing, pistons axially slidable in and pivotally movable with the cylinders, a driven eccentric, a ring journaled on the eccentric, circumferentially spaced pivotal connections between the ring and the pistons, respectively, means for limiting the angular movement of the ring on the eccentric to control said pivotal connections for imparting re-
15 ciprocating movement to the pistons, and means controlled by the pivotal movement of the cylinders for controlling the intake and exhaust of fluid for compression in the cylinders by the pistons.

30 4. A compressor comprising: a casing, a series of cylinders pivotally mounted in the casing, pistons axially slidable in and pivotally movable with the cylinders, a driven eccentric, a ring journaled on the eccentric, circumferentially spaced pivotal connections between the ring and the pistons, respectively, means for limiting the angular movement of the ring on the eccentric to control said pivotal connections for imparting recipro-
35 cating movement to the pistons, said limiting means including a stem rigid with and project-
40 ing outwardly from the ring, and means controlled by the pivotal movement of the cylinders for controlling the intake and exhaust of fluid for compression in the cylinders by the pistons.

45 5. A compressor comprising: a casing, a series of cylinders pivotally mounted in the casing, pistons axially slidable in and pivotally movable with the cylinders, a driven eccentric, a ring journaled on the eccentric, circumferentially spaced pivotal connections between the ring and the pistons, respectively, means for limiting the angular movement of the ring on the eccentric to control the pivotal connections for imparting recipro-
50 cating movement to the pistons, said limiting means including a stem rigid with the ring and a guide pivotally mounted in the casing and in which the stem is slid-
55 able, and means controlled by the pivotal movement of the cylinders for controlling the intake and exhaust of fluid for compression in the cylinders by the pistons.
